UNITED STATES PATENT OFFICE.

ABRAHAM ALBERT FREEDMAN, OF CHICAGO, ILLINOIS, ASSIGNEE OF ONE-HALF TO
SAUL S. SOLOWAY, OF CHICAGO, ILLINOIS.

SANITARY TELEPHONE MOUTHPIECE.

1,416,275.

Specification of Letters Patent. Patented May 16, 1922.

Application filed May 11, 1921. Serial No. 488,553.

To all whom it may concern:

Be it known that I, ABRAHAM ALBERT FREEDMAN, a citizen of the United States, residing at Chicago, in the county of Cook and State of Illinois, have invented a certain new and useful Improvement in Sanitary Telephone Mouthpieces, of which the following is a full, clear, concise, and exact description, reference being had to the accompanying drawings, forming a part of this specification.

The invention relates to sanitary caps for telephone mouthpieces, speaking tubes, and the like.

The primary aim of this invention is to provide a readily destructible cap of the character referred to which may be quickly applied to a telephone or speaking tube mouthpiece for use during a conversation to prevent deposit of moisture, bacteria or other undesirable collections in the mouthpiece, whereby to prevent the transmittal of diseases and to obviate danger to the health of the user.

Another aim of the invention is to construct a cap, for the above purpose, from a readily destructible and cheap material, such as relatively stiff paper coated with paraffine or the like, and which does not offer material impedance or disturbance to the passage of sound to the diaphragm of the telephone transmitter, and yet prevents effectively the deposit of moisture or deleterious germs in the mouthpiece itself.

It is further intended that means be incorporated in the cap for retaining the same temporarily fixedly upon or within the mouthpiece, the cap having the portion forming the bottom or end wall thereof composed of relatively thin perforated material to permit the ready transmittal of sound therethrough.

The invention is intended to be constructed of a single sheet of material so as to lend toward quantity production, and consequently economic output.

Other aims and advantages of the invention, together with a more concrete understanding of the same, may be obtained from the following detailed description and the claims taken with an inspection of the accompanying drawing, in which

Figure 1 is a longitudinal section of a telephone mouthpiece showing my invention applied thereto;

Fig. 2 is an enlarged similar view of the sanitary cap;

Fig. 3 is a perspective view of the cap;

Fig. 4 is a sectional view of a modified form of the invention.

Referring now to the drawing, and particularly Figure 1, 10 is a telephone mouthpiece of the conventional form, perforated at 11, and threaded at 12 for connection to the transmitter, not shown. Now referring in addition to Figs. 2 and 3, the cap of my invention is received within the flaring tapering annular wall 13 of the mouthpiece, and to this end preferably comprises a frusto-conical hollow body 14 composed of sufficiently heavy paper or the like to withstand the slight pressure required to force the cap into the mouthpiece, the inner or smaller end of said body having a relatively thin closing or end wall 15 of paper, if desirable, constructed integrally with the body. The body and end wall both may be and preferably are coated with an antiseptic solution. To permit passage of sound, yet arrest any germ laden moisture delivered from the speaker's lips, the wall 15 is perforated with two slits 16 and 17 relatively at substantially right angles, the resultant tapered tongues 18-18 being alternately bent inwardly and outwardly as best shown in Figure 3. The slight vibration of these tongues or the vibration of the walls of the cap have no audible effect upon the spoken sounds delivered to the transmitter.

For retaining the cap when inserted into the mouthpiece, an annular flange 19 is formed on the outer or larger end thereof by rolling the same, this flange being substantially circular in cross section and terminating in an annular friction gripping portion 20; the flange, when the cap is inserted, embracing the outer margin 21 of the mouthpiece and the portion 20 frictionally impinging the outer surface of the mouthpiece, thus temporarily sufficiently retaining the sanitary cap.

In the modified form of the invention, all the features of the preferred form are adhered to, with the exception that perforations 22 are provided in the wall 15 instead of the slits.

It will be observed that the features of a cap wherein are the moisture arresting but sound liberating bottom or end wall, retaining flange, and antiseptic impregnation, and

simplicity withal are important. The article is readily adapted to both telephone and speaking tube mouthpieces, and its possibilities in quantity production, and if desired, advertising, are particular features thereof.

While a specific embodiment with regard to shape and size has been described, minor changes in the details thereof may be made, 10 particularly with regard to the nature of the coating and the impregnating antiseptic mediums, without departing from the spirit of the invention and scope of the claims.

What I claim is:

- 15 1. The combination with a telephone mouthpiece, of a sanitary cap therefor comprising a tapering body composed of relatively thick paper provided with an end wall of thin paper perforated, and a flange on one

end of said body for engagement with the 20 mouthpiece.

2. An article of manufacture, comprising a frusto-conical hollow body composed of paraffine paper having a relatively thin end wall provided with cross slits, the tongues 25 formed thereby being bent alternately inwardly and outwardly of the said end wall.

3. An article of manufacture, comprising a frusto-conical hollow body composed of paraffine paper having a relatively thin end 30 wall provided with cross slits, the tongues formed thereby being bent alternately inwardly and outwardly of the said end wall, and an annular flange on the larger end of said body.

In witness whereof, I hereunto subscribe my name this 29th day of April A. D., 1921.

ABRAHAM ALBERT FREEDMAN.
